(57) **CLAIM**

The ornamental design for a merchandise display tray, as shown and described.

DESCRIPTION

FIG. 1 is a front perspective view of a merchandise display tray showing our new design;

FIG. 2 is an exploded front perspective view thereof;

FIG. 3 is a front view thereof;

FIG. 4 is a left side view thereof, the right side being a mirror image;

FIG. 5 is a rear view thereof;

FIG. 6 is a top plan view thereof;

FIG. 7 is a bottom plan view thereof; and,

FIG. 8 is a front perspective view of an alternate embodiment thereof showing multiple dividers.

The broken lines shown in FIGS. 1-8 represent optional dividers, fastener apertures, and reinforcement beads on the lateral walls of the tray, that form no part of the claimed design.
